UNITED STATES PATENT OFFICE

2,507,952

WINDOW SHADE GUIDE

Arthur Baron, Englewood, N. J.

Application December 11, 1946, Serial No. 715,563

1 Claim. (Cl. 160—268)

1

This invention relates generally to window shade devices, and more particularly to a combined guide and stop member for window shades, adapted to be installed in pairs, one on either side of the shade and secured to the window casing.

It is well understood that other devices have been developed and used for the same general purposes as this present invention, for example, a window shade stop which is the subject matter of a patent issued to Stich under #1,806,373, in which a single slot is provided to guide the window shade. This device, in common with other devices of like character, has the disadvantageous tendency to bind on the window shade, causing the window shade to loop above the stop member, especially when the device works loose or free enough to turn on the supporting screw, it being understood that all these devices are subject to considerable impact and strain placed thereupon by the shade in normal usage. Furthermore, devices of this character heretofore developed have been very limited in the application thereof to different types of window casings.

It is an object of this invention, therefore, to provide a double slotted guide and stop member which, in functioning as a guide member, will have a greatly lessened tendency to work loose from the window frame and will under all conditions tend to align itself so that the slots are retained at all times in proper operative position relative to the blind.

Another object of this invention is to provide a guide member which will not bind on the shade or cause the looping of the shade above the member.

Still another object of this invention is to provide a handy stop member limiting the upward movement of the blind.

And another object of this invention is to provide a device of this character in which the operative portion of the device is spaced from the attaching means therefore, fraying of the edges of the blind being thus prevented and the device is made generally more versatile in application.

And a last object to be specifically mentioned is to provide a window shade guide in a form making the same inexpensive and practicable to manufacture, extremely simple to install and use, and which will be generally efficient and durable in service.

With these and other objects in view as will appear hereinafter, this invention resides in certain novel features of construction, combination and arrangement of parts as will be hereinafter

described in detail and particularly set forth in the appended claims, reference being had to the accompanying drawings which form a material part of this application, and in which:

5 Figure 1 is a front elevational view of a window frame, sash and blind with a pair of devices designed according to this invention applied thereto in operative position;

Figure 2 is a vertical sectional view of this invention and a contiguous portion of a window blind used therewith, the view being essentially taken on the line 2—2 in Figure 1; and

15 Figure 3 is an enlarged fragmentary view of contiguous portions of a window frame and a blind with this invention operatively applied thereto, the shade being shown in elevation and the other portions of the figure being shown in vertical section.

Similar characters of reference designate similar or identical parts and portions throughout the specification and throughout the views of the drawings.

20 Referring now to the drawing, which illustrates a preferred embodiment of this invention, a window frame 10 having a window sash 12, is provided with a window shade 14 mounted on a roller 16 at the top of said frame according to conventional design and here represented in order to show the environment therewith this invention is adapted to be used.

25 This invention contemplates the provision of flat discs or plates 18, centrally apertured to receive an attaching screw 20 whereby this flat plate is firmly secured to the window frame 10 as hereinafter described. Integral with said plate 18 and extending normally from one side thereof is a hollow cylinder 22. The end of the cylinder 22, remote from the attaching screw 20, is provided with diametrically disposed slots 24 and 26, these slots being slightly wider than the thickness of the shade wherewith they are to be used, and extend to points 28 and 30 intermediate the ends of the cylinder. It is preferred that the edges of the slotted portions be beveled to lessen the tendency of the device to fray the edges of the window blind 14.

30 Obviously, the plate 18 need not be circular and the size of this plate may be considerably greater than the base portion of the member 22. It will also be understood that the cylindrical form of the member 22 is here used illustratively and other shapes being used, the essential feature of this invention is the provision of a hollow member having walls which may be slotted to provide two spaced shade contacting members, the mem-

ber being essentially hollow in order to provide for the convenient mounting of the device by a screw 20. It would, however, be within the province of this invention to extend the plate 18 beyond the periphery of the member 22 and to secure the device in position on a window frame by means of screws inserted through the extending portion of the plate.

In using this device the upper limit to which the blind will normally be raised must be predetermined and the devices are placed, one on either side of the blind, with the edges of the blind inserted in the slots 24 and 26, the attachment of the devices to the window frame 10 being, of course, achieved prior to the insertion of the blind in the slots. In functioning as a stop member the upper edge of the reinforced lower end 32 of the blind abuts the lower surfaces of the members 22, effectually preventing the raising of the blind beyond the devices. The provision of the two points of contact for the blind in each unit of this device tends to preserve the blind in vertical position so that the weight of the blind beneath the devices is fully utilized in eliminating the tendency of the blind to loop above the devices.

With the foregoing description of the mechanical details of this invention in view, it will be obvious that this device has many advantages over other devices of like character and that the prime purpose of the invention, the avoidance of the tendency of window blinds to flap, will be efficiently achieved.

It is thought that the above description will enable anyone to make and use this invention and further description thereof is deemed unnecessary.

Having thus described this invention what is claimed as new and desired to be secured by Letters Patent is:

A device comprising a base securable to a window casing and a hollow member extending from one face of said base having two diametrically disposed parallel slots in the walls thereof adapted to receive one edge of a window shade, frictional contact of the shade in said two slots constantly urging said device into proper positional relationship with said shade and preventing binding, said slots extending equal distances from the end of said member remote from said base to points intermediate the length of said member whereby the shade is spaced from said attaching member.

ARTHUR BARON.
